US0D1007899S

(12) **United States Design Patent** (10) **Patent No.:** **US D1,007,899 S**
(45) **Date of Patent:** **** Dec. 19, 2023**

(54) **CUSHION**

(71) Applicant: **Jingang Yang**, Sichuan (CN)

(72) Inventor: **Jingang Yang**, Sichuan (CN)

(**) Term: **15 Years**

(21) Appl. No.: **29/800,574**

(22) Filed: **Jul. 22, 2021**

(30) **Foreign Application Priority Data**

Jun. 18, 2021 (CN) 202130376963.2

(51) **LOC (14) Cl.** **06-09**

(52) **U.S. Cl.**

USPC **D6/601**

(58) **Field of Classification Search**

USPC D6/595, 596, 597, 601, 604; D24/183, D24/184, 185; D21/803, 804, 805, 809; D28/20

CPC .. A47C 7/425; A47G 9/10; A47G 2009/1018; A47G 9/1081; A61F 5/01; A61G 13/121
